W. H. REICHARD

RECEIVER FOR CONTINUOUS INDUCTIVE TRAIN CONTROL SYSTEMS

Filed Nov. 27, 1925

FIG. 2

FIG. 4

FIG. 3

W. H. Reichard,
Inventor
Neil H. Reaton,
his Attorney

UNITED STATES PATENT OFFICE.

WADE H. REICHARD, OF ROCHESTER, NEW YORK, ASSIGNOR TO GENERAL RAILWAY SIGNAL COMPANY, OF ROCHESTER, NEW YORK.

RECEIVER FOR CONTINUOUS INDUCTIVE TRAIN-CONTROL SYSTEMS.

Application filed November 27, 1925. Serial No. 71,830.

This invention relates to automatic train control and more particularly concerns an inductive receiving device for automatic train control systems of the continuous inductive type.

In the continuous inductive type of train control system, the operation of the car-carried apparatus, comprising suitable brake control, cab signal or other devices, is governed in accordance with influences corresponding to traffic conditions continuously received from the trackway. The transmission of these influences from the trackway is usually accomplished by means of alternating currents flowing in the track rails under favorable traffic conditions, these currents acting through an intervening air gap to induce voltages in suitable car-carried receiving coils.

In systems of the type described, the control currents in the track rails are necessarily small and the car-carried receiving coils must be arranged with their magnetic circuits in close proximity to the track rails in order that appreciable voltages may be induced therein. It is desirable that the receiving coils be provided with a suitable magnetic core to collect the flux surrounding the track rails, and that the coil and core structure be ruggedly constructed to withstand the vibration and jar of train operation.

With the above and other considerations in mind it is proposed in accordance with the present invention to provide a receiving coil and core structure for continuous inductive automatic train control systems which is designed to be rigidly secured to a locomotive or other railway vehicle in close proximity to the track rails, the construction of which is simple, rugged and durable, the core structure of which is arranged to collect a maximum of the flux surrounding the track rails, and the coil structure of which is constructed to withstand the jar and the vibration of train operation without injury to the wiring thereof.

Other objects, advantages and characteristic features of the invention will be apparent as the description thereof progresses.

In describing the invention in detail, ref-

erence will be made to the accompanying drawings in which:

Fig. 1 is an inside end view of the receiving structure of the present invention;

Fig. 2 is a side view of the receiving coil and core, the coil structure being shown in section;

Fig. 3 is a plan view of the receiving structure; and

Fig. 4 is a section along the line 4—4 of Fig. 2, viewed in the direction of the arrows.

The receiving structure of the present invention comprises in general a laminated iron core having an enlarged pole piece secured to one end thereof and carrying a coil or winding thereon. The core is preferably mounted at right angles to the track rail 1 as shown in Fig. 2, and the coil and pole piece are in the present instance located on the inner end of the core, that is, on the end of the core which extends toward the center of the vehicle.

Referring to the drawings, the core structure comprises a horizontal portion 2 of magnetic laminated material. The two outer laminæ or side plates 3 are preferably of a greater thickness than the others, thereby adding to the strength and rigidity of the core and protecting the thinner laminæ. Two upwardly extending hangers or brackets 4 are secured to the outer end of the core structure 2 by means of the bolts 5 and 6 as shown, these bolts together with the bolts 7, 8 and 9 also serving to secure the laminæ of the core structure 2 together. The hangers 4 are provided with holes 10 to permit them to be secured to a railway vehicle.

Two angle brackets or hangers 11 are secured to the opposite faces of the inner end of the core portion 2 by means of the bolt 9. These hangers 11 comprise the vertically extending angle portions 12 provided with the bolt holes 13, and the horizontally extending foot portions 14 as most clearly shown in Fig. 1. A horizontally extending laminated pole piece 15 of magnetic material is secured to the under side of the horizontally extending foot portions 14 of the hangers 11 by means of the bolts as shown. The pole piece 15 is thus mounted parallel to the track rail 1. The pole piece 15 comprises a stack of

laminæ of magnetic material, having the side plates 17 similar in thickness and in function to the plates 3 of the core portion 2, the entire pole piece structure being secured together by the rivets 18 as clearly shown. The heads of the bolts 16 which support the pole piece are preferably countersunk into the lower face thereof, whereby a smooth lower face of the pole piece is obtained.

Interposed between the under side of the core structure 2 at the inner end thereof and the upper face of pole piece 15, is a small laminated core block 19. This block 19 is of general rectangular shape in cross section, having a slot 20 in the upper face thereof for the reception of the bolt 35. The block 19 is retained in place by the pressure exerted thereon by the core structure 2 and the pole piece 15, and is also held between the plate 38 and the inner face of the coil structure C.

The coil structure, indicated as a whole as C, includes a coil or winding 24 having a slightly tapered inner bore as shown, and protected by several layers of linen tape and horn fibre 25. Suitable insulating washers 26 and 27 are placed on either end of the coil, these washers being composed of a tough insulating material such as moulded asbestos. Several layers of manila rope 28 are wound outside of the coil 24 between the washers 26 and 27, this rope serving to strengthen and to protect the winding 24. The entire coil structure including the rope 28 and the washers 26 and 27 is enclosed by several layers of linen tape 29 and is impregnated with a suitable water-proof compound.

The coil structure C is firmly secured to the core structure by means of the tapered wedges 30 and 31. These wedges are constructed of a suitable material such as cast-iron and are of general semi-circular form as best shown in Fig. 4. Depressions 32 and 33 are formed at the edges of the wedges 30 and 31 respectively, for the reception of the enlarged heads 34 of the bolts 35. The wedges 30 and 31 are so constructed that when placed within the coil structure C, their adjacent ends do not quite meet, thus providing two longitudinal openings, 36 and 37 as clearly shown in Fig. 4, for the reception of the bolts 35.

In assembling the coil and core structure, the coil structure C is first placed on the core with the portion 2 extending through the opening in the coil and with the coil structure in engagement with the angle hangers 11 as shown in Fig. 2. The wedges 30 and 31 are then placed between the core portion 2 and the coil structure C in the position shown in Fig. 4, the bolts 35 are inserted between the ends of the wedges 30 and 31 and the plate 38 is passed over the

inner ends of these bolts and drawn into engagement with the inner end of the core structures 2 and 19 and the angle hangers 11. The lock washers 39 and the nuts 40 are then placed on the bolts 35, and the wedges 30 and 31 are firmly drawn up between the core structure 2 and the coil structure C, thus rigidly securing these parts together without danger of chafing or cutting the windings.

A junction box B is preferably secured to the core portion 2 at approximately its mid-point by the bolts 7 and 8 as shown. This junction box B is provided with an angularly disposed opening to which a flexible armored cable 41, containing the leads from the coil 24, is connected through a coupling 42. A second opening 43 is provided in the upper face of an outwardly projecting portion 44 of the junction box B, this opening 43 being preferably threaded to receive the usual conduit connection. A removable cover 45 is provided on the top surface of the junction box B and is held in place by the machine screws 46, this cover serving to permit ready access to the interior of the junction box for the purpose of making the necessary electrical connections.

The core and coil structure described are secured to a locomotive or other railway vehicle by means of the hangers 11 and 4, the relation of the core structure to the track rail 1 being as shown in Fig. 2. The hangers 4 and 11 are preferably secured to the usual bumper bar of a locomotive by means of suitably shaped iron straps which are variously formed to meet the requirements of various locomotive structures. When alternating control currents flow in the track rail 1, an alternating magnetic flux exists in the neighborhood of this track rail, which flux is collected by the pole piece 15 and the core structure 2, and thus links the winding 24. Alternating voltages corresponding to the alternating flux surrounding the track rail are thus induced in the coil 24 and are transmitted to the car-carried control apparatus through the armored cable 41 and the junction box B.

From the description given, it is seen that a simple, compact, and rugged core and coil structure has been provided. The magnetic circuit is so arranged that an appreciable flux is collected thereby when alternating currents flow in the track rails. The coil structure is strongly constructed, well insulated and firmly secured to the core, and the electrical connection of the winding with the car-carried apparatus is facilitated by the junction box B.

Although the present invention has been described in connection with a single specific embodiment, it should be understood that certain changes and modifications may be made without departing from the spirit of

the invention as defined by the amended claims.

What it is desired to secure by Letters Patent is:—

- 5 1. In an influence receiving device for automatic train control systems, a core of magnetic material, a coil on said core, and a junction box secured to said core adjacent said coil.
- 10 2. An influence receiving device for automatic train control systems comprising, a laminated core of magnetic material, brackets secured at right angles to said core at one end thereof, a pole piece secured to said brackets and a coil on said core rigidly secured against said brackets.
- 15 3. An influence receiving device for automatic train control systems comprising, a core of magnetic material, a pair of brackets secured at right angles to said core at one end thereof, said brackets serving to permit the attachment of said core to a vehicle, a pole piece secured to said brackets, and a coil on said core rigidly secured against said brackets.
- 20 4. An influence receiving device for automatic train control systems comprising, a core of laminated magnetic material, brackets secured to said core at right angles thereto, a coil on said core adjacent said brackets, tapered wedges between said coil and said core and means for drawing said wedges towards said brackets, whereby said coil is rigidly secured to said core against said brackets.
- 25 5. In an influence communicating device for automatic train control systems, a core of magnetic material having brackets secured to the ends thereof, a coil on said core having a tapered inner bore, tapered wedges between said core and said coil and means for drawing said wedges towards said brackets on one end of said core, whereby said coil is rigidly secured to said core adjacent one of said brackets.
- 30 6. In an influence communicating device for automatic train control systems, a core of magnetic material, a coil structure on said core comprising a winding of electrical conducting material having a tapered inner bore and a plurality of layers of non-conducting material wound outside of said winding, and
- 35 means for rigidly wedging said winding on said core.
- 40 7. In an influence receiving device for automatic train control systems, a core of magnetic material, a coil structure on said core comprising, a winding of conducting wire, washers of insulating material on the ends of said winding and extending radially beyond the outer circumference thereof, a plurality of layers of rope wound around said winding between said washers, and means for rigidly securing said coil structure to said core.
- 45 8. In an influence receiving device for automatic train control systems, a core of magnetic material, a coil structure on said core comprising an insulated winding of conducting wire and a plurality of layers of protective insulating material wound over said winding, and tapered wedges between said coil structure and said core, whereby said coil structure is rigidly secured to said core.
- 50 9. An influence receiving device for train control systems, comprising, a laminated core of magnetic material, brackets secured at right angles to the core at one end thereof, a pole piece spaced from the core and screwed to the brackets, a core block positioned between the core and the pole piece, and a coil on the core.
- 55 10. An influence receiving device for train control systems, comprising, a laminated core of magnetic material, brackets, secured at right angles to the core at one end thereof, a pole piece spaced from the core and screwed to the brackets, a core block positioned between, and interconnecting the core and the pole piece, and a coil on the core.
- 60 11. An influence receiving device for train control systems, comprising, a laminated core of magnetic material, brackets secured at right angles to the core at one end thereof, a pole piece spaced from the core and screwed to the brackets, a core block positioned between the core and the pole piece, and a coil on the core, rigidly secured against said bracket, the pole piece projecting beyond the edge of said coil.

In testimony whereof I affix my signature.
WADE H. REICHARD.
